(57) **CLAIM**

The ornamental design for a jaw design for a surgical instrument, as shown and described.

DESCRIPTION

FIG. 1 is a perspective view of an embodiment of a jaw design for a surgical instrument;

FIG. 2 is a front view of the jaw in FIG. 1;

FIG. 3 is a back view of the jaw in FIG. 1;

FIG. 4 is a right side view of the jaw in FIG. 1;

FIG. 5 is a left side view of the jaw in FIG. 1;

FIG. 6 is a top view of the jaw in FIG. 1;

FIG. 7 is a bottom view of the jaw in FIG. 1;

FIG. 8 is a perspective view of an embodiment of a jaw design for a surgical instrument;

FIG. 9 is a front view of the jaw in FIG. 8;

FIG. 10 is a back view of the jaw in FIG. 8;

FIG. 11 is a right side view of the jaw in FIG. 8;

FIG. 12 is a left side view of the jaw in FIG. 8;

FIG. 13 is a top view of the jaw in FIG. 8;

FIG. 14 is a bottom view of the jaw in FIG. 8;

FIG. 15 is a perspective view of an embodiment of a jaw design for a surgical instrument;

FIG. 16 is a front view of the jaw in FIG. 15;

FIG. 17 is a back view of the jaw in FIG. 15;

FIG. 18 is a right side view of the jaw in FIG. 15;

FIG. 19 is a left side view of the jaw in FIG. 15;

FIG. 20 is a top view of the jaw in FIG. 15; and,

FIG. 21 is a bottom view of the jaw in FIG. 15.

The figures illustrate a jaw design for a surgical instrument. In the figures, the broken lines depict environmental subject matter only and form no part of the claimed design.
